SAMPLE PIN TICKET

Harry E. Elson, Dallas, Tex.

Application December 7, 1938, Serial No. 244,441

1 Claim. (CL. 40—25)

This invention relates to new and useful improvements in pin tickets such as are employed in the marking of fabrics, garments and the like.

One object of the invention is to provide a pin ticket whereby said ticket may be first attached to a bolt of material, garment or the like having a continuous portion whereby samples or swatches may be attached to said ticket, thus, a sample of said material or garment may be shown very easily and without cause for disturbing said material or garments.

Another object of the invention is to provide a pin ticket of the nature described, said ticket having means thereon for attaching the ticket upon a bolt of material or garments to be sold and being so constructed that samples or swatches may also be affixed to said ticket, and having means for suitably protecting the fastening means whereby said means may do no damage either to an adjacent article or to the hands of a person called upon to handle the aforementioned bolt of material, garment or the like to which the improved ticket may be fastened upon.

Another object of the invention is to provide a pin ticket of the character described, said ticket having scoring near to the edges of said faces, whereby a larger retaining compartment for bulky materials may be had with the least amount of effort and having a neat appearing folded edges.

The invention will be more readily understood from a reading of the following specification and by reference to the accompanying drawing wherein a disclosure of the invention is made and wherein:

Figure 1 is an isometric view of a pin ticket constructed in accordance with the invention.

Figure 2 is an isometric view similar to Figure 1 showing the invention affixed to a portion of an article to be sold.

Figure 3 is another isometric view wherein the invention is shown as being attached both to the article to be sold and a sample of the same.

Figure 4 is an elevation of the ticket showing the invention's construction, and

Figure 5 is a longitudinal sectional view of the invention completely attached as shown in Figure 3.

Figure 6 is a detail view of a pin adapted for use in connection with the ticket.

In the drawing the numeral 10 designates a ticket constructed in accordance with the invention. The ticket is comprised of three connected foldable main flaps 11, 12 and 13. At its outer

end the flap 13 is connected to a tab 14, the purpose of this tab will be hereinafter described.

Fold lines 15 and 16 are formed by scoring the material of which the ticket is made. Additional scoring may be provided on the flaps at 17. The scoring 17 is provided whereby a deeper fold may be had thereby accommodating thicker or bulkier materials. A fold line 18 connects the tab 14 with the flap 13.

A wire staple or double pointed pin 19 is permanently fastened to the outer edge of the flap 11. A complementary aperture 20 is provided in the flap 12 adjacent the fold 16, whereby when flap 12 and connected members are folded in an adjacent position to that of the flap 11, the pin 19 may enter the aperture 20, said staple or pin 19 is bent downward and outward to cause a connection of the flaps 11 and 12.

A pin 21 (Figure 6) similar to the pin 19 insertable in apertures a located in the flap 12 and at the opposite end of said flap in relation to the aperture 20, the pin therefore being located adjacent the fold line 15. A complementary aperture 22 similar to the aperture 20 is made in the flap 13 adjacent the fold line 18. This aperture performs the same operation in conjunction with the pin 21 as is performed by the aperture 20.

It is to be noted that pin 21 is not put in place until after the ticket has been applied to the goods in order to insure against injury to the hands or fabric. Moreover, once in place, the pin is concealed by flap 24.

A transverse slot 23 is formed in the flap 13 at a point near the aperture 22 and being located between said aperture and the fold line 16. This slot receives the reduced portion 24 of the tab 14. As such as the pin 21 is entered through the aperture 22 and therewith fastened, the tab portion 24 is inserted in the transverse slot 23. With this arrangement a protective cover for the sharp points of the pin 21 is provided. Needless to say, a similar protective cover is provided by the flap 13.

In operation, the flap 11 is placed over a portion of the article 25 to be sold, the pin or staple 19 is forced into and through the article, said pin then passes through the aperture 20 in the flap 12, said flap having been folded into an adjacent position to that of the flap 11. The pin 19 is then bent upon the now lower side of the flap 12, thereby simultaneously confining the article 25 between the flaps 11 and 12 by means of the pin 19 and aperture 20 and also fastening the ticket 10 to the aforementioned article 25, Figure 2.

A sample or swatch 26, of the article is then laid upon the flap 12 and the staple 21 is forced through a portion of the sample 26. The flap 13 is then folded over the sample 26 in an adjacent position to that of the flap 12 and on the opposite side of the sample thereof.

5 The pin 21 is then inserted into and through the aperture 22, said pin then being bent to confine the sample between the flaps 12 and 13
10 of the ticket 10, said ticket having been fastened to the article 25 as has been explained.

The flap 14 is then bent back toward the fold line 16; the portion 24 of said tab is then inserted into the slot 23, thus covering the pin
15 points 21 completely, whereby said points may in no way damage either adjacent articles or the hands of persons called upon to handle the articles upon which the invention may be fastened.

If desired one or both sides of the ticket 10
20 may be printed (Figure 4) whereby suitable indicia may be noted thereon.

From the foregoing it will be seen that a pin ticket simple in construction and cheap in manufacture may be had. Said ticket being so constructed as to be affixed to the article to be sold and having a sample of said article affixed to the ticket, thereby doing away with any need of a cumbersome "sample book" and the loss of time connected with said book.

30 At the same time a ticket having sufficient space for descriptive and instructive indicia thereon; and also said ticket being so constructed as to prevent danger to who may come in contact with said ticket.

It is to be noted that the size and shape of the invention and the material of which the same is constructed may be changed in accordance with the article to be ticketed.

Manifestly, the construction as shown and described is capable of some modification and such modification as may be construed within the scope and meaning of the appended claim is also considered to be within the spirit and intent of the invention.

10 What is claimed is:

As a new article of manufacture, a pin ticket for garments, samples and the like comprising a strip of material of foldable sections capable of receiving sales markings, one end section provided with transverse scores adjacent one end thereof and having a slot and a foldable tab receivable in an aperture in said section spaced from said slot, the next adjacent section having a slot and apertures spaced from said slot at its 20 opposite end, a pin staple carried by the free end of the opposite end section and receivable in the slot in said next adjacent section after having penetrated fabric disposed between said two latter sections, and a pin staple carried by said 25 next adjacent section and receivable in the slot in said one end section after having penetrated fabric disposed between said last mentioned sections with the prongs of the staple adapted to be concealed by said foldable tab.
